(57) **CLAIM**

The ornamental design for a vehicle, as shown and described.

DESCRIPTION

FIG. 1 is a front, left side, perspective view of the vehicle; FIG. 2 is a front, left side, perspective view thereof, wherein the convertible top is stowed and the side windows are rolled down;

FIG. 3 is a rear, left side, perspective view thereof, wherein the convertible top is raised and the side windows are rolled up;

FIG. 4 is a rear, left side, perspective view thereof, wherein the convertible top is stowed and the side windows are rolled down;

FIG. 5 is a rear, top, right side, perspective view thereof, wherein the convertible top is stowed and the side windows are rolled down;

FIG. 6 is a left side view thereof, wherein the convertible top is raised and the side windows are rolled up;

FIG. 7 is a right side view thereof, wherein the convertible top is raised and the side windows are rolled up;

FIG. 8 is a left side view thereof, wherein the convertible top is stowed and the side windows are rolled down;

FIG. 9 is a right side view thereof, wherein the convertible top is stowed and the side windows are rolled down;

FIG. 10 is a top view thereof, wherein the convertible top is raised and the side windows are rolled up; and,

FIG. 11 is a top view thereof, wherein the convertible top is stowed and the side windows are rolled down.

The even broken lines shown in the drawings illustrate portions of the vehicle that forms no part of claimed design.
